UNITED STATES PATENT OFFICE.

EDWARD C. JENNER, OF ALLEGAN, MICHIGAN.

DOOR-OPERATOR.

SPECIFICATION forming part of Letters Patent No. 349,592, dated September 21, 1886.

Application filed May 3, 1886. Serial No. 200,945. (No model.)

To all whom it may concern:

Be it known that I, EDWARD C. JENNER, a citizen of the United States, residing at Allegan, in the county of Allegan and State of Michigan, have invented certain new and useful Improvements in Door-Operators; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to door-operators, and has for its object to simplify and improve this class of devices, whereby the mechanism is made more positive in its operation and reduced to a more compact form.

It consists in the novel construction and combination of the several parts, more fully hereinafter set forth, claimed, and shown in the annexed drawings, in which—

Figure 1 is a view of the lower portion of a door, showing the floor beneath in section, exposing the door-operating mechanism. Fig. 2 is a sectional view on the line XX of Fig. 1. Fig. 3 is a detail view of the operating-gearing. Fig. 4 is a section on the line YY of Fig. 2, looking in the direction of the arrow, parts being removed.

The door A is hinged in the usual manner above the floor B, beneath which is a space for the reception of the operating mechanism supported by uprights or beams C. An opening 35 is formed in the floor near the front edge of the door at right angles to the plane of the door when closed. A board, D, fitting in said openings bears upon rods or plates E, supported on cranks e e'. The cranks e are secured to and 40 project in the same lateral direction from a rock-shaft, F, mounted in bearings in the beams or uprights C beneath the flooring. The cranks e' are located beneath the shaft F, and are supported by the uprights. They are somewhat 45 longer than the cranks e, to permit the board D, having a vertical movement without any lateral or side play practically.

An arm, G, depending from the shaft F connects with a toothed disk or mutilated gear, H, 50 journaled on a shaft or stud, I, by a pitman, g. A vertical rod or shaft, J, mounted in bear-

ings and preferably in line with the axis about which the door swings, is provided with a pinion, K, meshing with the teeth g' of the disk or mutilated gear H. A rod, j, secured to the door at one end, and having its other end keyed to or otherwise rigidly fastened to the shaft J, forms the connection between the door and its operating mechanism. The rod j is preferably the prolongation of the pivot for securing the two parts of the hinge together, and is secured to that part of the hinge fastened to the door, so that in the rotation of the rod it will cause a corresponding movement of the door.

The board D extends sufficiently far on one side of the plane of the door, so that a person stepping thereon will effect an opening of the door without the latter interfering with or preventing the continued advance of the person. In practice a depression of the board rocks the shaft F in its bearings, throwing the arm G to one side and rocking the toothed disk or mutilated gear about its axial line or support, and effects a rotary motion of the shaft J and rod j, thereby opening the door. The parts are 75 returned to their normal position, when the weight is removed from off the board, by a weighted lever, L, extending from the shaft F.

The board D projects some distance above the level of the floor, and is provided with a cap, D', extending beyond its edges to overlap the joint between it and the flooring. The space between the edges of the cap and the floor may be covered by a hinged flap, M, as shown.

Having thus fully described my invention, what I claim as new, and desire to secure by Letters Patent, is—

1. The combination, with the door and a rod secured thereto and projecting therefrom, of a movable board, a rock-shaft, a crank connecting the rock-shaft with the board, an arm projecting from the rock-shaft, a pitman connecting with the arm at one end, and gearing connecting the opposite end of the pitman with the rod projecting from the door, and a weighted lever extending from the rock-shaft, substantially as and for the purpose described.

2. The combination of the door, a rod projecting therefrom in line with its hinges, a movable board, a rock-shaft, cranks located at different levels, the one extending from the

rock-shaft, plates supported on the outer ends of the cranks and forming a rest for the movable board, an arm projecting from the rock-shaft, a toothed plate or disk journaled on a short shaft, a pitman connecting the plate and arm, a short vertical shaft secured to the rod projecting from the door, a pinion keyed thereon and meshing with the toothed disk, and a

weighted lever extending from the rock-shaft, substantially as set forth.

In testimony whereof I affix my signature in presence of two witnesses.

EDWARD C. JENNER.
